UNITED STATES PATENT OFFICE.

WILLIAM J. STOOP, OF WHEELING, WEST VIRGINIA.

APPARATUS FOR FEEDING POWDERED COAL.

Application filed December 5, 1923. Serial No. 678,774.

To all whom it may concern:

Be it known that I, WILLIAM J. STOOP, a citizen of the United States of America, and resident of Wheeling, county of Ohio, 5 and State of West Virginia, have invented certain new and useful Improvements in Apparatus for Feeding Powdered Coal, of which the following is a specification.

This invention relates broadly to powdered coal installations for furnaces, and more specifically to feeding and distributing apparatus for powdered fuel.

The primary object of the invention is to provide, in association with a furnace or 15 fire-box for boilers, an apparatus whereby powdered coal is supplied at low velocity to the fire-box of a boiler, or to a furnace, and is effectively distributed over a relatively wide area for facilitating combustion.

20 A further object is to provide an apparatus of the character described embodying controllable means whereby the rate of supply of air for mixing with the fuel is automatically regulated.

25 In describing the invention in detail, reference is herein had to the accompanying drawings, in which—

Figure 1 is a top plan view of the invention, a portion of the distributor-head casting being broken away;

30 Figure 2 is a section taken substantially on line 2—2, Fig. 1, showing the invention applied to the arch of the fire-box of a boiler;

35 Figure 3 is a view of the distributor head partly in front elevation and partly in section, illustrating its application to the arch of the fire-box, the latter being shown in transverse section;

40 Figure 4 is an enlarged detail section of the arch and the nozzles of the distributor head; and—

Figure 5 is an enlarged side elevation of the shutter box.

45 Referring to said drawings, 1 indicates generally the crown of a furnace or the arch of the fire-box of a water tube boiler designed to employ powdered coal as fuel. Said wall, hereinafter termed an arch, as 50 shown in Figs. 3 and 4, is constructed of tile or blocks 1^a of a suitable refractory material supported by parallel longitudinally extending I-beams 2.

55 Located in transversely aligned relation over the arch is plurality of distributor nozzles 3, preferably made of cast iron, to and

through which the powdered coal is delivered, said nozzles being of inverted frusto-pyramidal form and having their smaller ends seated in correspondingly 60 shaped seats 4^a formed at the upper ends of vertically disposed slot-like openings 4 provided in an underlying row of the arch-blocks 1^a, said openings constituting passageways through which the fuel is introduced in the fire-box. Said nozzles 3 are supported by the I-beams 2, each carrying on opposite lateral walls thereof fixed lugs 5 which rest upon the tops of the adjacent beams, as shown in Figs. 3 and 4.

65 Mounted upon the upper ends of the nozzles 3 is the lower end of a sheet metal casing 6 which is rectangular in horizontal section for embracing the upper portions of the aligned nozzles and which is substantially of inverted frusto-pyramidal form. The casing 6 has attached thereto and opening through the upper portion of the front wall thereof the mouth portion of a fan-shaped spreader 7 to which coal from the pulverizer (not shown) is supplied through a thereto-attached supply pipe 8. Said spreader has a capacity greatly in excess of that of the pipe 8, and the aggregate discharge area of the nozzles is greater than 70 that of said pipe; consequently, the velocity of the fuel through said spreader is materially reduced, resulting in the delivery of said fuel to the fire-box at relatively low velocity.

75 The rear wall 6^a of the casing 6 is preferably disposed vertically, while the front wall 6^b is inclined downwardly and forwardly from the spreader 7 to the nozzles, as shown in Fig. 2. Surmounting said casing 80 and having the rear wall thereof in the same plane with the rear wall 6^a, or formed by an upward extension of the latter, is a box-like enclosure 9 defining an inlet passage-way for air which is admitted for mixing 85 with the fuel in the lower part of said casing prior to the delivery of the latter to the fire-box. One or more damper-like shutters 10 are mounted over the top of said enclosure 9 for controlling the admission 90 of air. As herein shown, said shutters are fixed upon rods or shafts 11 which are rotatably mounted on the upper part of a cap 12 carried on the top of the enclosure 9. Arms 13 fixed on adjacent ends of said 95 shafts 11 normally occupy depending positions in which said shutters are main-

tained in closing relation to the open top of said cap 12, as shown in Fig. 3. A horizontally disposed bar or link 14 has pivoted connection with the outer ends of said arms 5 and is adapted to be suitably connected, as by a cable 15, to an automatic furnace-damper controlling device (not shown) which may be of any of the various commercial pressure-regulated types, whereby 10 said dampers are elevated and lowered in accordance with the demands of the furnace.

Fixed within the casing 6 and extending in a downwardly and forwardly inclined direction 15 from the lower end of the front wall of the enclosure 9 to a level somewhat above the discharge end of said casing is a baffle plate 16 which serves to prevent the admitted draughts of air from creating a 20 back pressure which might interfere with the delivery of the powdered coal. The lower edge of said baffle is suitably spaced from the rear wall 6^a of the casing, being carried by cleat-like straps 17 mounted on 25 said wall, as shown in Figs. 1 and 2.

Superposed upon terminal flanges 3^a formed on the adjacent sides of the upper ends of the nozzles 3 are upright dividers 18, of pyramidal form, which serve to split up 30 the coal delivered downward within the casing 6 and to make a theoretically equal division between adjacent nozzles.

The casing 6, spreader 7, and nozzles 3 constitute a distributor head which is particularly effective for accomplishing a proper distribution of powdered coal throughout boiler fire boxes and the combustion chambers of furnaces. Due to the 35 relieving of the fuel-supply pressure when the fuel reaches the spreader and to the resultant low velocity at which the fuel is delivered to the fire-box through the arch 1, practically complete combustion of said fuel occurs in the upper portion of the fire- 40 box, or at a height relatively remote from the ash-collection bed, thus reducing ash-fusion to a minimum.

What is claimed is—

1. In apparatus for feeding powdered 45 coal to furnaces and boiler fire-boxes, the combination with an overlying arch having alined feed passages therein, of a plurality of nozzles of inverted frusto-pyramidal form in communication with said passages,

dividers located in intermediate overlying relation to said nozzles, a casing having its lower end embracing the upper ends of said nozzles, a fuel supply pipe opening into said casing, controllable means for introducing air through the top of the casing, and baffle means whereby the admitted air is delivered for mixing with the coal at a point intermediate the level of said supply opening and the level of said dividers. 55

2. In apparatus for feeding powdered 60 coal to furnaces and boiler fire-boxes, the combination with an overlying arch having alined feed passages therein, of a plurality of nozzles of frusto-pyramidal form in communication with said passages, dividers located in intermediate overlying relation to said nozzles, a casing having its lower end communicating with the upper ends of said nozzles, a fuel supply pipe opening laterally into the upper end of said casing, 65 controllable means for introducing air vertically into said casing, and a transversely disposed baffle depending within said casing between the fuel-supply opening and the opposite casing wall for directing admitted air past said opening and delivering same in mixed relation to the fuel at a level below said opening. 70

3. In apparatus for feeding powdered 75 coal to furnaces, the combination with a furnace arch having a feed passage therein, of a distributor head arranged for feeding coal through said passage, said distributor head comprising a hopper-like casing having its delivery end disposed in open communication with said passage, a fuel supply pipe opening into said casing at a level remote from said delivery end, controllable means for introducing air at atmospheric pressure into said casing through the top of the latter, and a baffle arranged transversely between the fuel supply pipe opening and the opposite wall of the casing and depending to a level adjacent to said delivery end of the casing, said baffle serving 80 to prevent back pressure of air in said fuel supply pipe by delivering the air for mixing with the fuel at a level adjacent to said delivery end. 85

In testimony whereof, I affix my signature. 90

WILLIAM J. STOOP.
